(57) CLAIM

The ornamental design for a perfume bottle, as shown and described.

DESCRIPTION

FIG. 1 is a top perspective view of a perfume bottle showing the new design;

FIG. 2 is a side elevation view thereof;

FIG. 3 is a top plan view thereof;

FIG. 4 is a bottom plan view thereof;

FIG. 5 is a top perspective exploded view thereof in an alternate configuration;

FIG. 6 is a side elevation view thereof; and,

FIG. 7 is an opposite side elevation view thereof.

The broken lines shown in the drawings illustrate portions of the perfume bottle that form no part of the claimed design.
